GREASING MECHANISM

Bernard D. Kaiser, South Bend, Ind., assignor to Bendix Aviation Corporation, South Bend, Ind., a corporation of Delaware

Application October 6, 1955, Serial No. 538,924

2 Claims. (Cl. 184—15)

This invention relates in general to conveyor mechanisms and in particular to an automatically operable power operated mechanism for greasing the rollers of the trolleys of a conveyor mechanism.

It is an object of my invention to provide a simple, effective and easily serviced power operated greasing mechanism of relatively few moving parts said mechanism serving to inject a lubricant into the trolley rollers of a conveyor mechanism when the same is in operation.

Yet another object of my invention is to provide an automatically operative fluid motor operated greasing mechanism for lubricating the trolley mechanism of a conveyor said greasing mechanism including a plurality of double acting motors operable, as the trolleys of the conveyor pass a given point on the conveyor mechanism, to actuate the greasing mechanism to inject a lubricant into the trolley mechanism of the conveyor.

Other objects of the invention and desirable details of construction of parts will become apparent from the following detailed description of an illustrative embodiment of the invention, taken in conjunction with the accompanying drawing illustrating said embodiment in which:

Figure 1 is a side elevational view of the greasing mechanism of my invention;

Figure 2 is a view, largely in section, disclosing details of the control valve of the mechanism of Figure 1;

Figure 3 is a sectional view; disclosing other details of the control valve mechanism of Figure 1;

Figure 4 is a view, partly in section, disclosing one of the lubricating nozzle mechanisms of the mechanism of Figure 1; and

Figure 5 is a view, taken on the line 5—5 of Figure 1, disclosing one of the springs for controlling the operation of the lubricating nozzles of my invention.

Referring now to Figure 1, disclosing a preferred embodiment of my invention, a conveyor mechanism adapted, say, to transport material from place to place in a factory building, includes the usual I-beam rail structure 10 having secured thereto channel shaped cross members 12, one of which is disclosed in said figure. A plurality of movable trolleys 14 each including straps 16, rollers 18, and a two part support member 20, are mounted on the I-beam and are moved along said beam by a power driven chain 22. Each of the trolleys supports a basket or other suitable container 24 filled with the material to be conveyed.

The principal feature of my invention lies in the mechanism for automatically greasing the rollers 18 of the trolley mechanism as they pass a certain point in the conveyor system. To this end there are provided two double acting fluid pressure motors 26 and 28, preferably compressed air operated, adjustably mounted on the channel member 12. As is disclosed in Figure 1, the two motors extend in alignment with the member 12 and are spaced apart a sufficient distance to allow the trolleys 14 to pass between them.

2

Since the motors 26 and 28 and their mountings are duplicates only one of said motors and its mounting will be described. The motor 26 includes a casing 30 and a piston therein, not shown, said casing being secured by straps 32 and fastenings 34, to a rectangular plate 36.

Overlapping plates 38 and 40 fixedly secured, respectively, to the plate 36 and the channel 12 provide means for vertically spacing the motor 26 the desired distance from said channel. This adjustment is effected by fastenings

10 42 extending through registering slots in the plates 38 and 40. A rectangular plate 44, mounted on the plate 36 by supporting plates 46, is recessed to slidably receive a rectangular shaped plate 48. This plate 48 is secured by means including a support

15 member 50, to a rod 52 which is connected to the motor piston, not shown; and to the plate 48 there is also connected a trigger mechanism 56. To this trigger mechanism, which is of any well known design and to which no claim is made, there is connected a conduit 62 said

20 conduit being connected at its other end to a bracket member 64 which is connected to the plate 48 and member 50 at their juncture. The conduit 62 extends through the member 64 and is connected to a nozzle unit including a lubricant transmitting tube 66 having a cap 68 at

25 its outer end adapted to fit over a grease fitting mounted in the center of the bearing of the rollers 18. A lubricant transmitting conduit 67 interconnects the trigger unit 56 with a pressure source 69 of suitable lubricant. As disclosed in Figure 4, the tube 66 is housed within

30 a cylindrical casing 70 which is fixedly secured to the support member 50. A washer 72, keyed to the tube 66 and located at about the center of the casing 70, serves in part to provide two chambers within the casing said

35 chambers housing springs 74 and 76 which serve to correctly position the tube 66 with respect to the rollers 18 and to prevent any damage to the cap 68 and rollers when the greasing operation is performed; for the spring 74 will yield when the motor piston is moved to bring the cap into contact with the rollers. To the plate 36 there is

40 secured, by fastenings 78, a bumper member 80; and the trigger mechanism 56 moves into contact with the cushioned end 81 of this bumper member 80 when the motor 26 is energized to effect the greasing operation.

Describing now the valvular mechanism for controlling the operation of the motors 26 and 28, this mechanism preferably includes a power operated 4-way valve 82, Figure 1 which controls both of said motors. Referring to Figures 2 and 3 disclosing details of this valve, a casing 84, provided with cylinder ports 86 and 88, exhaust ports

50 90 and 92, and an intake port 94 to which is connected a conduit 95 leading to a source of air under pressure, is bored to slidably receive a cylindrical valve member 96. This member 96 is provided with ports 98, 100, 102 and 104, there being a plurality of each, said ports registering with the aforementioned ports as described herein-after. A wall member 106 within the member 96 serves to block off the ports 98 and 100 from the ports 102 and 104. A spring 108, housed within a cap 110 and contacting one end of the valve member 96, serves to bias said member to the right, Figure 2, to its position disclosed in said figure. When the ported casing 84 and ported valve member 96 are in their relative positions disclosed in Figure 2, the port 100 registers with a duct

55 112 in the casing. As to the remainder of the valve mechanism disclosed in detail in Figure 3, a casing member 114 secured to the casing 84 is bored to receive a fixed tubular valve member 116 which is bored to slidably receive a movable valve member 118. This member is biased upwardly, to the position disclosed in Figure 3, by a spring 120 and is moved downwardly by the armature 122 of a solenoid 124 se-

60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945

cured to the casing 114. When the solenoid is de-energized the spring 120 serves to move the valve member 118 and the armature 122 to the position disclosed in Figure 3. The solenoid is controlled by a normally open switch 126 which is closed by each trolley just before it reaches a point in line with the caps 68. The hollow valve member 118 is provided with ports 128, 130 and 132 which, as described below, register with a duct 134, a duct 136, and a chamber 138 which registers with an exhaust port 140 in the casing 114. The duct 134 registers with a compartment 142 outlined by a valve member 144 and the walls of a recess 146 in the casing 114. The valve member 144 abuts one end of the valve member 96.

Describing now the operation of the mechanism of my invention and completing the description of said mechanism, it will be assumed that the trolleys are in motion in a direction away from the plane of the paper disclosing Figure 1. Then just before each trolley reaches the plane of the tubes 66, said plane being normal or substantially normal to the plane of the trolleys, a striker member 148 secured to the trolley serves to close the switch 126 to energize the motors 26 and 28. This switch, which is secured to the bottom of the channel 12, is of course, positioned so that the motors operate to inject the lubricant into the bearings of the rollers 18 when said rollers are in line with the tubes 66. It is to be remembered that in this lubricating operation the outward movement of the motor piston results both in moving the caps 68 into contact with the bearings of the rollers and in moving the trigger 56 into contact with the bumper 80.

Describing the operation of the 4-way valve 32 to effect this operation, energization of the solenoid 124 serves to move the armature 122 and valve member 118 downwardly, Figure 3, to interconnect the conduit 112, at this time leading to the source of air pressure, with the compartment 142 of the valve; and this operation serves to move the valve member 96 to the left, Figure 2, against the compression of the spring 108, to interconnect said source of air pressure with a conduit 150. This conduit 150 is connected to conduits 152 and 154 which are connected, respectively, to the ends of the motors 26 and 28 remote from the trolleys that is the outer end of said motors. The aforementioned operation of the valve also serves to vent the inner ends of the motors to the atmosphere via conduits 158 and 160, a conduit 156, the valve member 96, and the port 90 of the valve. With this lubricating operation the tubes 66, by virtue of the play allowed by the size of openings 99 and 99' in the casing 70, to move with the trolley for a very short period of time, that is, until the switch 126 has been opened to again energize the double acting motors to return the motor pistons to their off positions. Each tube is, however, returned to its normal position by a spring 103 connected to the tube and to a bracket 105 secured to the channel 12; all as is disclosed in Figures 1 and 5.

Describing the return operation of the motors 26 and 28 when the switch 126 is opened as above described, the solenoid 124 is de-energized thereby making it possible for the spring 120, to move the valve member 118 and armature 122 to their positions disclosed in Figure 3; and this operation results in a venting of the compartment 142 to the atmosphere with a resultant expansion of the spring 108, Figure 2, to move the valve member 96 to the right to the position disclosed in Figure 2.

As will be noted from an inspection of Figure 2, this operation results in connecting the inner ends of the motors to the source of air pressure and venting the outer ends of the motors to the atmosphere. The motors are thus energized to return the trigger 56 and the tubes 66 to their off positions of Figure 1 preparatory to another lubricating operation of the motors when the next trolley closes the switch 126.

There is thus provided a simple, compact and effective power operated mechanism for automatically lubricating the rollers of the trolleys of a conveyor system.

I claim:

1. A lubricating mechanism for automatically lubricating the rollers of the trolleys of a conveyor mechanism as said trolleys move past the lubricating mechanism, said lubricating mechanism including a fixedly mounted support member, a greasing mechanism secured in large part to the support member, said greasing mechanism comprising two aligned fluid motors each comprising a casing and a piston member, support means for, in part, adjustably securing the two casings to the fixedly mounted support member, two grease transmitting means, each including a trigger control unit, for effecting a greasing operation of the rollers when the motors are energized, means, having a portion thereof slidably mounted on a portion of the support means, for supporting the grease transmitting means, and means, fixedly secured to the support means, for cooperating with the trigger control units to effect their operation; the entire mechanism being operable, with an energization of the two motors, to move portions of the two grease transmitting means toward the rollers of a trolley and, at the end of the stroke of the said portions, to actuate the trigger control units to effect a greasing operation of the rollers.

2. A lubricating mechanism for automatically lubricating the rollers of the trolleys of a conveyor mechanism as said trolleys move past the lubricating mechanism, said lubricating mechanism including a fixedly mounted support member, a greasing mechanism secured in large part to the support member, said greasing mechanism comprising two aligned fluid motors each comprising a casing and a piston member, support means for, in part, adjustably securing the two casings to the fixedly mounted support member, two grease transmitting means, each including a trigger control unit comprising a fixed part and a movable part, for effecting a greasing operation of the rollers when the motors are energized, means, having a portion thereof slidably mounted on a portion of the support means and a portion connected to the motor piston, for supporting the grease transmitting means, and means, comprising fixed bumper members, fixedly secured to the support means, for cooperating with the trigger control units to effect their operation; the entire mechanism being operable, with an energization of the two motors, to move portions of the two grease transmitting means toward the rollers of a trolley and, at the end of the stroke of the said portions, to actuate the trigger control units, by a movement of their movable part, to effect a greasing operation of the rollers.
